UNITED STATES PATENT OFFICE.

CHRISTIAN RUDOLPH SACK, OF PLAGWITZ, NEAR LEIPSIC, SAXONY,
GERMANY.

STEAM-CULTIVATOR.

SPECIFICATION forming part of Letters Patent No. 427,117, dated May 6, 1890.

Application filed December 4, 1888. Serial No. 292,676. (No model.)

To all whom it may concern:

Be it known that I, CHRISTIAN RUDOLPH SACK, a citizen of Germany, residing at Plagwitz, near Leipsic, in the Kingdom of Saxony, Germany, have invented a new and useful Improvement in Steam-Cultivators, of which the following is a specification.

My invention relates to an improvement of Patent No. 386,161, dated January 17, 1888, granted to me; and it consists of the improvement hereinafter fully described and claimed.

In the accompanying drawings, Figure 1 is a top view of part of a steam-cultivator with my improvement attached. Fig. 2 is a side view of the same. Fig. 3 is a plan on a reduced scale, showing two pulleys upon a rail.

The horizontal pulley A is supported on a beam *a*, to the ends of which bearings *b* are attached, in which wheels *c*, grooved or double-flanged, are supported in a diagonal position.

To the central part of the beam *a* an arm *f* is securely attached, carrying at its end a movable rod *h*, the lower end of which has a foot-plate *h'* hinged to it, capable of being fastened by suitable bolts to the ground.

g is a box attached to the beam *a* and arm *f*, to receive tools and ballast or any other weights to counteract the strain upon the horizontal wheel *A*. The grooved or flanged wheels *c* travel upon corresponding inclined rails *d*, secured to frames or sleepers *e*, fastened, by means of bolts *l*, securely to the ground.

When the carriage is to be moved, the foot-plate *h'* is loosened and the after end of the arm *f* slightly lifted, whereby the motion of the carriage is made more easy.

What I claim is—

In combination with the beam *a*, supporting the horizontal wheel *A*, the inclined bearings *b*, inclined double-flanged wheels *c*, inclined rail *d*, and the projecting arm *f*, with rod *h* and hinged foot-plate *h'*, substantially as and for the purpose described.

In testimony whereof I have signed my name to this specification in the presence of two subscribing witnesses.

CHRISTIAN RUDOLPH SACK.
